6 Claims. (Cl. 260—583)

This is a division of application Ser. No. 374,235, filed June 8, 1964.

This invention relates to novel nitramides and to the conversion of the nitramides to nitramines.

The primary nitramines are a class of compounds having a wide variety of uses, particularly in rocket propellants and explosives. The energy provided by these compounds in a propellant or explosive composition is dependent to a considerable extent on the nitramine being present in essentially pure form. If the nitramine component in the composition is contaminated or diluted with impurities or by-products from the synthesis reactions, the overall effectiveness of the propellant or explosive is reduced. Previously attempts have been made to prepare primary nitramines by direct nitration of the free amine, or by dehydration of the nitrate salt. However, it has been found that primary nitramines, such as 3,6-dinitraza-1,8-octane dinitramine, cannot be prepared in good yield by direct nitration of the corresponding amine or by dehydration of the nitrate salts of the corresponding primary amine because both of these techniques involve the contacting of the primary nitramine, as it is formed, with strong acid which causes excessive decomposition of the desired product. This decomposition which occurs in the prior art processes yields the primary nitramine in very impure form, making the compounds generally unsuitable for direct use in propellants and explosives. Removal of these contaminants involves many involved and costly purification procedures.

It has now been found that primary nitramines can be prepared from novel nitramides in good yield and without the need for contacting the primary nitramine with a strong acid. The primary nitramines of our invention are directly obtained in high purity, thus avoiding elaborate after-treatment and purification. According to our invention, the primary nitramines are obtained by preparing a nitramide by reaction of the corresponding amide with an ionic nitrating agent, followed by hydrolysis. This novel technique will be more fully understood, in both its broad and specific aspects, from the discussion which follows. It can be seen, however, that by the practice of our invention, the contact of the ionic nitrating agent with the free primary amine is altogether eliminated.

It is an object of this invention to prepare primary nitramines without contacting the primary nitramine with strong acid. It is still a further object of this invention to prepare nitramines by a method which will provide these compounds in better yield and greater purity than those methods previously known. Still another object of this invention is to prepare novel nitramides. These and other objects of this invention will be apparent from the description which follows.

One of the starting materials in the preparation of the primary nitramines, according to the method of this invention, are the nitramides having the following general formula:

wherein A and A' are alkylene radicals, preferably lower alkylene radicals having from 1 to about 10 carbon atoms; i.e., methylene, ethylene, pentamethylene, decamethylene, etc.; R and R' are alkyl radicals, preferably lower alkyl radicals, having from 1 to about 10 carbon atoms, such as methyl, ethyl, and decyl; and n is a small whole number of from 1 to about 4. The above-mentioned radicals may be branched or straight-chained. These novel compounds are referred to as nitramides in this patent since they contain, as terminal groups, the

radical wherein R' is as has already been defined.

The nitramides of the above formula are prepared by reacting (Reaction I) an ionic nitrating agent with a compound of the formula:

wherein A, A', R, R' and n are as defined above. In the above reaction, the choice of the ionic nitrating agent is not critical. Any of the common strong ionic nitrating agents such as nitric acid, mixtures of nitric acid and sulfuric acid, mixtures of nitric acid and acetic anhydride, and mixtures of methyl nitrate and sulfuric acid may be used. Ionic nitrating agents containing nitric acid are preferred.

Generally speaking, a solvent is not required in order to prepare the novel amides of our invention, according to Reaction I. However, if desired, any essentially inert solvent can be used, although carbon tetrachloride is preferred. The proportions of the nitramine and ionic nitrating agent employed in the above reaction are not critical. Preferably the ionic nitrating agent is used in an amount stoichiometrically in excess to the amount of the nitramide employed so as to drive the reaction to completion within a reasonable length of time. The reaction temperature may be varied over a wide range. The preferred range is from about -15°C . to about $+35^{\circ}\text{C}$.

The novel nitramides prepared in the above manner are converted to the nitramines by hydrolyzing the nitramides in accordance with the general reaction (Reaction II) set forth below.

wherein A, A', R, R' and n are as defined above. The amides undergo hydrolysis under basic conditions, such as by the addition of sodium hydroxide, potassium hydroxide, ammonium hydroxide, and the like, to the amide. Optimum results were obtained when the hydrolysis was conducted in an ammoniacal media. It is to be understood that hydrolysis of the amide with base yields the amine in the form of the basic salt. The free amine is then obtained by neutralizing the salt with a stoichiometric equivalent amount of an acid such as hydrochloric acid. In Reaction II, the reactants are ideally used in stoichiometrically equivalent amounts since this results in the most complete utilization of the reactants. However,

the proportions may be varied over a wide range without adversely affecting the reaction.

The preparation of the nitramine is preferably carried out by addition of the base to the nitramide. No solvents are ordinarily necessary. However, if desired, a polar solvent such as water may be used.

It is desirable that the hydrolysis of the nitramide be carried out at a temperature between about 0° C. and about 100° C., although this reaction range is not critical to our invention.

Pressure is not critical in the preparation of the nitramide or the nitramine. Therefore the reactions may be run at any pressure, atmospheric pressure being most convenient.

The nitramides and nitramines of this invention are normally solids and may be isolated in conventional manner by filtration, evaporation and/or crystallization.

To more clearly illustrate our invention, the following examples are presented. It is to be understood, however, that these examples are intended merely as illustrative embodiments of the invention and should not be construed as being limitative of the scope of said invention in any way. In the examples percentages are by weight unless otherwise indicated.

Example I.—Preparation of N,N'-dinitro-3,6-dinitraza-octamethylene-bis-acetamide

To a 500 ml. flask, fitted with a mechanical stirrer, thermometer and dropping funnel, was added 150 ml. of acetic anhydride. Keeping the temperature of the mixture at 0° C. to 5° C., 150 ml. of 100 percent nitric acid was added dropwise, and then 17.5 grams of 3,6-dinitraza-octamethylene-bis-acetamide was added. The reaction mixture was stirred for 45 minutes at 0° C. to 5° C. and poured on ice. The white solid which formed was collected, washed with water and dried in vacuo over potassium hydroxide. Recrystallization from ethylene dichloride gave 12.5 grams (55.8 percent) of N,N'-dinitro-3,6-dinitraza-octamethylene-bis-acetamide, having a melting point of 127° C. to 128° C. The elemental analysis of the product is as follows:

Calc'd for $C_{10}H_{18}N_8O_{10}$, percent: C, 29.27; H, 4.42; N, 27.31. Found, percent: C, 29.00; H, 4.25; N, 27.21.

The 3,6-dinitraza-octamethylene-bis-acetamide employed in the above example is prepared by the reaction of sodium methoxide and acetic anhydride with 3,6-dinitraza-1,8-octane diamine hydrochloride, as is more fully disclosed in U.S. Patent No. 2,967,198, issued Jan. 3, 1961.

Example II.—Preparation of N,N'-dinitro-4-nitraza-heptamethylene-bis-caproamide

To a flask is added equal volumes of acetic anhydride and 100 percent nitric acid. The temperature is maintained at about 0-10° C. and 4-nitraza-heptamethylene-bis-caproamide is added to the mixed acids in increments until the total diamine added is about stoichiometrically equivalent to the amount of nitrating agent present. The mixture is agitated while being maintained at about 5-10° C. and then poured on ice. Recrystallization of the product in accordance with the procedure of Example I yields N,N'-dinitro-4-nitraza-heptamethylene-bis-caproamide in the form of a solid product.

Example III.—Preparation of N,N'-dinitro-3-nitraza-pentane-bis-acetamide

In a one-liter 3-necked flask, fitted with a mechanical stirrer, thermometer, and dropping funnel was placed 250 ml. of 100% nitric acid. The acid was cooled to -10 to 0° and 250 ml. of acetic anhydride was added dropwise at this temperature. To the acid solution was added 35.0 g. (0.15 mole) of 3-nitrapentane-bis-acetamide. After 75 minutes at -5 to 0° the solid had dissolved. The solution was poured on ice, the white solid collected, washed with

water, and dried, 21.6 g. (44.5%), M.P. 68-70°. Recrystallization from carbon tetrachloride raised the melting point to 72-73°.

Analysis.—Calc'd for $C_8H_{14}N_6O_8$, percent: C, 29.82; H, 4.38. Found, percent: C, 29.93; H, 4.38.

Example IV.—Preparation of 3,6-dinitraza-1,8-octane dinitramine

To 6.5 grams of N,N'-dinitro-3,6-dinitraza-octamethylene-bis-acetamide (prepared according to Example I) was added 25 ml. of 28 percent ammonium hydroxide. The solid dissolved with the evolution of heat. The solution was cooled in an ice bath and acidified with dilute hydrochloric acid. The white solid which precipitated was collected, washed with water, and dried in vacuo over potassium hydroxide. Recrystallization from acetone-chloroform gave 5.1 grams (98.7%, based on the amide) of 3,6-dinitraza-1,8-octane dinitramine in the form of white needles, having a melting point of 177-178° C. The elemental analysis of the product is as follows:

Calc'd for $C_8H_{14}N_8O_8$, percent: C, 22.09; H, 4.33; N, 34.35. Found, percent: C, 22.33; H, 4.28; N, 34.14.

Example V.—Preparation of 4-nitraza-1,7-heptane dinitramine

To N,N'-dinitro-4-nitraza-heptamethylene-bis-caproamide (prepared as in Example II) is added an equivalent amount of 28 percent ammonium hydroxide. The solid is allowed to dissolve and is then acidified with dilute hydrochloric acid. The solid precipitate is collected, washed and dried to give 4-nitraza-1,7-heptane dinitramine in good yield.

Example VI.—Preparation of 3-nitraza-1,5-pentane dinitramine

To 21.6 g. (0.067 mole) of N,N'-dinitro-3-nitraza-pentane-bis-acetamide was added 50 ml. of water and 50 ml. of concentrated ammonium hydroxide solution. The addition of the base caused the solid to dissolve with the evolution of heat. The solution was warmed on the steam-bath for five minutes, cooled, and acidified with dilute hydrochloric acid. The white solid which precipitated was collected, washed with water, and dried, 15.0 g. (94%), M.P. 146-150°. Recrystallization from methyl ethyl ketone raised the melting point to 152-153°.

Calc'd for $C_4H_{10}N_6O_6$, percent: C, 20.17; H, 4.23; N, 35.29. Found, percent: C, 20.83; H, 4.37; N, 35.73.

Other nitramides and nitramines can be prepared according to the above examples. For example, 4,7-dinitra-decamethylene-bis-butyramide is nitrated with a solution of methyl nitrate and sulfuric acid to form N,N'-dinitro-4,7-dinitra-decamethylene-bis-butyramide. This latter compound is then reacted sequentially with ammonium hydroxide and hydrochloric acid to form 4,7-dinitra-1,10 decane dinitramine.

In the preparation of the nitramines and nitramides, according to the method of this invention, it is sometimes desirable to agitate the ingredients so as to assure more intimate contact, and thereby an improved rate of reaction.

The nitramines and nitramides of this invention contain a plurality of nitro groups, and thus are inherently useful as explosives. The nitramide and nitramine compounds of our invention will find utility in solid rocket propellants. More specifically, these compounds may be used to increase the specific impulse of the known solid propellants used in intermediate and intercontinental ballistic missiles, such as the aluminized polyurethane systems and those based on carboxy-terminated polybutadiene-azirindinyl curative binders.

The novel nitramides as well as the nitramines of this invention can also be used in any conventional explosive missile or rocket as the main explosive charge. An example of such a missile is disclosed in United States Patent No. 2,470,162, issued May 17, 1949. The high explosives of this invention can be used in such a device by

simply packing the explosive in powdered form into the warhead of the missile.

This application is a continuation-in-part of applicants' copending U.S. patent application, Ser. No. 209,276, filed July 9, 1962.

It will be understood that various modifications may be made in this invention without departing from the spirit or the scope of the appended claims.

We claim:

1. The method of preparing nitramines of the formula:

which comprises reacting a compound of the formula:

with an ionic nitrating agent to form the nitramide of the formula:

wherein in each of the above formulae, R and R' are lower alkyl radicals, A and A' are lower alkylene radicals, and n is a small whole number of from 1 to about 4; hydrolyzing the thus formed nitramide to the nitramine

5 salt by the addition of a base, and neutralizing said salt to the nitramine by the addition of a mineral acid.

2. The method of claim 1 wherein the hydrolysis is followed by the addition of hydrochloric acid.

3. The method of claim 1 wherein the ionic nitrating agent contains nitric acid, and the hydrolysis is carried out by the addition of ammonium hydroxide.

4. The method of preparing 3-nitraza-1,5-pentane dinitramine which comprises reacting 3-nitraza-pentane-bis-acetamide with nitric acid, followed by hydrolysis with ammonium hydroxide and neutralization with hydrochloric acid to form said dinitramine.

5. The method of preparing 3,6-dinitraza-1,8-octane dinitramine which comprises reacting 3,6-dinitraza-octamethylene-bis-acetamide with nitric acid, followed by hydrolysis with ammonium hydroxide and neutralization with hydrochloric acid to form said dinitramine.

6. The method of claim 5 wherein the reaction with the nitric acid is carried out at a temperature of about 0° C. to about +10° C.
